UNITED STATES PATENT OFFICE.

JAMES A. ALLISON AND ORAMEL H. SKINNER, OF INDIANAPOLIS, INDIANA, ASSIGNEES
TO THE PREST-O-LITE COMPANY, OF INDIANAPOLIS, INDIANA, A CORPORATION OF
INDIANA.

STARTING APPARATUS FOR INTERNAL-COMBUSTION ENGINES.

1,151,150.

Specification of Letters Patent. Patented Aug. 24, 1915.

Application filed November 7, 1911. Serial No. 659,006.

To all whom it may concern:

Be it known that we, JAMES A. ALLISON and ORAMEL H. SKINNER, citizens of the United States, residing at Indianapolis, in the county of Marion and State of Indiana, have invented certain new and useful Improvements in Starting Apparatus for Internal-Combustion Engines, of which the following is a specification.

10 The object of our said invention is to provide an apparatus for supplying a charge of acetylene gas, or other explosive fuel, drawn from the supply tank of a motor vehicle lighting system, or other appropriate supply, to the several cylinders of a multiple cylinder explosive engine, to be ignited by any appropriate sparkler, for starting said engine, and, further, to provide such an apparatus so that its operation will definitely 20 measure and supply a uniform charge to each cylinder.

It consists, further, in an arrangement for feeding acetylene gas from the same source to the intake manifold of the engine 25 as may be necessary to continue the operation thereof until the carburetor is working properly and supplying a satisfactory mixture for the purpose, all as will be hereinafter more fully described and claimed.

30 Referring to the accompanying drawings which are made a part hereof and on which similar reference characters indicate similar parts: Figure 1 is a view of the front end of an automobile, diagrammatically 35 illustrating the application and use of our invention thereon. Fig. 2, an elevation of a special form of pump and connections, which form an important part of our said invention, as seen when looking downwardly 40 from the point 2 in Fig. 1. Fig. 3, a central longitudinal section through the same on the dotted line 3—3 in Fig. 4. Fig. 4, a cross section on dotted line 4—4 in Figs. 2 and 3. Fig. 5, a cross section on dotted line 5—5 45 in Figs. 2 and 3. Fig. 6, a detail view illustrating the check-valve used between the pump cylinders and the pipe leading to the engine cylinders. Fig. 7, a detail view illustrating the check-valve used at the connection of said pipes with the engine cylinders. Fig. 8, a detail view illustrating the pres-

sure reducer on an enlarged scale, as seen from dotted line 8—8 in Fig. 1. Fig. 9, a detail view illustrating a modified form of pump, and Fig. 10, a detail view illustrating 55 a modified form of check-valve.

In said drawings the portion marked A represents the vehicle body, B the engine, and C the acetylene tank. These several parts are, or may be, of a common form 60 such as are in every day use on automobiles and require no special description.

The acetylene tank C is preferably of the "Prest-O-Lite" type such as is in general use. It has a pressure reducer, or regulator, 65 C¹ attached thereto, of the automatically operating type which in itself is no part of the present invention, but is important as one of the elements contributing to the success and practicability of its operation. 70

The pump which constitutes a leading element of our invention comprises a body 10 containing a central suction cylinder 11 surrounded by as many discharge cylinders as the engine has cylinders. In the drawings 75 we have illustrated a four cylinder engine and also a four discharge cylinder pump. The four discharge cylinders are each connected with the central suction cylinder 11 by a port-hole 12 located near the outer end 80 thereof. The ends of body 10 are closed by suitable plates 13 and 14 attached in a suitable manner, or one end, as 14, may be cast in piece therewith. A piston 15 is mounted in each discharge cylinder on a piston rod 85 16 which extends out through head 13 and is attached to a common handle 17. A similar piston P is mounted in the suction cylinder 11 on a piston rod 18 which is also secured to and operated by the handle 17. A 90 check-valve casing 19 is mounted in the inner end of each discharge cylinder and connected by a pipe 20 to a check-valve casing 21 mounted in the head of each engine cylinder B adjacent to the spark plug s. A 95 boss 23 is formed on end 14 having an aperture leading into the suction cylinder 11 and the end 22 of a pipe 24 connects therewith in any appropriate manner, and leads to the pressure regulator C¹ of the acetylene tank 100 C. A valve 25 is mounted in said pipe 24 adjacent to the dash a of the vehicle, the

stem 26 of said valve projecting through said dash and being provided with an appropriate hand wheel for operating the same. A branch pipe 27 leads from said 5 pipe 24 on the side of valve 25 toward supply tank and is provided with a valve 28 adjacent to the dash *a* having a valve stem 29 extending through said dash and provided with a hand wheel by which it may be operated. Said branch 27 leads to and is connected with the intake manifold *b* of the 10 engine.

In order to secure the best results it is 15 important that the details of construction be accurately and perfectly developed, and to this end we have provided special forms of 20 check-valves which may be used to advantage, although other forms may be used successfully, and substituted therefor without 25 departing from our invention. In Fig. 6 we have illustrated, on a larger scale, the special form of check-valve 19, which consists of a casing screwed into a screw-threaded perforation in the end of each 30 pump cylinder (or otherwise appropriately secured) and having a screw-threaded outer end which is bored out to form a chamber in which a cylindrical valve 31 may operate, and is also formed with a smaller central 35 perforation 32 leading to within the pump cylinder. Around the inner end of said perforation 32 is formed a tapered seat for the cone-shaped end of said valve 31. An outer shell 33 is screwed onto the outer end of 40 casing 19 having a port 34 leading into the valve chamber. Said shell 33 is formed with a neck piece 35 to which a pipe 20 may be appropriately attached. A coiled spring 36 is mounted within hollow valve 31 to hold the same normally to its seat.

In Fig. 7 we have illustrated the preferred 45 form of check-valve for use in the end of the engine cylinder, the same comprising a casing or plug 21 screwed into a perforation in the engine cylinder and formed with a 50 valve chamber in its upper end and a port 44 leading therefrom into said cylinder. It has an L 40 on one side formed with a seat for a steel tail-piece 41 which is secured 55 therein by means of a screw-threaded collar 42 engaging with a shoulder on said tail-piece. A port 43 leads into the valve chamber within the plug 21. A valve comprising a weighted cylinder 45 with a cone-shaped 60 lower end is mounted in said valve chamber with its point seated upon a tapered valve at the inner end of port 42.

In Fig. 9 we have shown a modified form 65 of pump comprising two double acting cylinders divided by the pistons 50 and 51. One cylinder has an inlet valve 52 and a discharge valve 53 at one end and an inlet valve 54 and a discharge valve 55 at its other end, while the other cylinder

is similarly provided with an inlet valve 56 70 and an outlet valve 57 at one end and, an inlet valve 58 and an outlet 59 at its other end. The operation of the pistons, in either direction, draws a charge into each cylinder on one side and discharges one on the other, as will be readily understood. We also illustrate in Fig. 10 a modified form of 75 check-valve, merely to show one substitute form which may be found practicable.

The operation of our said invention is as follows: The engine being at a standstill, and it being desired to start the same, the operator opens valve 25 which establishes communication, through pipe 24, between pump 10 and the pressure reducing chamber 80 C¹ of the acetylene tank C. By drawing the pistons 15 outward to the extreme limit of their motion a definite quantity of the acetylene gas is drawn into suction cylinder 11 and at the same time a vacuum is created 85 in the discharge cylinders surrounding said suction cylinder. As soon as the pistons pass the port-holes 12, leading from the suction cylinder into said discharge cylinders, the gas rushes into the vacuum thus 90 created and each discharge cylinder receives its proportion of the charge of acetylene from cylinder 11. By reason of taking the acetylene from the low pressure chamber of the pressure regulator C¹ which is always 95 automatically maintained at a uniform pressure it is always drawn from a chamber containing gas at uniform pressure, which is usually very low, and not calculated to affect the operation of the pump. The pump, 100 therefore, always takes a definitely measured quantity of the acetylene gas at each suction stroke. The check-valves 31 hold the discharge cylinders closed during the suction stroke and thus a uniform vacuum is 105 created in each discharge cylinder so that as soon as the portholes 12, of uniform area, are uncovered each cylinder takes an equal proportion of the charge of the acetylene gas in suction cylinder 11. As soon as the 110 pistons start back on the discharge stroke ports 12 are covered and further communication between the suction cylinder and discharge cylinders is cut off so that no further acetylene gas can be taken into said 115 discharge cylinders until the next suction stroke of the pistons has been completed. The acetylene gas is forced by the discharge stroke of the pistons through check-valves 19, pipes 20 and check-valves 21 into the several engine cylinders adjacent to the spark plugs thereof. The spark circuit being then closed a spark is formed in the cylinder ready for the explosion, which takes place, and the engine started. Two other charges 125 are exploded, in turn, in the respective cylinders in the regular order. The fourth charge under this system will probably be 120

- exhausted, but the three explosions, under ordinary conditions, will be sufficient to continue the engine in motion until the carbureter is properly working and supplying the regular mixture to the cylinders. Under some conditions, as in very cold weather, when it takes longer for the carbureter to get into proper working condition, valve 29 may be opened and a supply of acetylene gas permitted to flow through pipe 27 to the intake manifold *b* of the engine and from thence to the respective engines, supplying the fuel to continue the engine in operation until the carbureter is working normally.
- 15 Valve 28 is then closed and the supply of gas cut off. Valve 25 may be closed, but in practice it has been found not necessary, inasmuch as the pressure of the gas in the side of the pressure regulator from which the supply is drawn is so low that it is not sufficient to overcome the friction between the pistons and the cylinders of the pump 10. This valve in practice, therefore, is necessary only to positively shut off the flow of gas, as when the car is idle.
- 20 Having thus fully described our said invention, what we claim as new and desire to secure by Letters Patent, is:
1. An apparatus for starting internal combustion engines comprising an explosive fuel supply, pipes leading therefrom to the engine cylinders, a pump interposed in said pipes formed with an intake cylinder to receive a measured charge from the supply at each suction stroke and a number of discharge cylinders corresponding to the number of engine cylinders and arranged to deliver to each engine cylinder a definite quantity of the explosive fuel at each discharge stroke, substantially as set forth.
2. An apparatus for starting internal combustion engines comprising an explosive fuel container, a pressure regulator attached thereto, pipes leading from the low pressure chamber of said pressure regulator to the several cylinders of the engine, a pump interposed in said pipes and formed with a suction cylinder and a number of discharge cylinders corresponding to the number of cylinders of the engine, each of which communicates with said suction cylinder through a port located near the limit of the suction stroke of the piston, the suction cylinder being connected with the supply and the discharge cylinders with the engines, and check-valves for controlling the ports leading from the discharge cylinders and the ports leading into the engine cylinder, substantially as set forth.
3. An apparatus for supplying explosive fuel to the cylinders of an internal combustion engine comprising a compound cylinder pump having a suction cylinder adapted to measure the charge and a number of discharge cylinders corresponding with the number of engine cylinders communicating therewith at the limit of the charge intake stroke, and suitable pipes connecting said pump with the supply and with the engine cylinders, substantially as set forth.
4. An apparatus for supplying explosive fuel to a multiple cylinder engine comprising a multiple cylinder pump having a suction cylinder connected with the explosive fuel supply and a different discharge cylinder connected with each engine cylinder, substantially as set forth.
5. An apparatus for starting internal combustion engines comprising a multiple cylinder pump having a suction cylinder and a discharge cylinder for each engine cylinder and arranged to supply a uniform charge at each discharge stroke of the pump, substantially as set forth.
6. An apparatus for starting internal combustion engines comprising an explosive fuel supply, a pressure regulator connected therewith, a pipe leading from the low pressure side of said regulator to a pump, said pump, pipes leading from said pump to the several engine cylinders, a branch pipe connected with the supply pipe at one side of the pump and leading to the intake manifold of the engine, and a valve for controlling the flow through said branch pipe, substantially as set forth.
7. An apparatus for starting internal combustion engines comprising an explosive fuel supply, a pipe leading therefrom to a measuring and injecting pump, pipes leading from said pump to the several engine cylinders, valves for controlling the flow through said pipes, a branch pipe connected with the supply pipe at one side of the pump and connected with the intake manifold of the engine, and a valve for controlling the flow through said branch pipe, substantially as set forth.
8. An apparatus for starting internal combustion engines comprising an explosive fuel supply, a pump having a central suction cylinder, a pipe connecting said cylinder with said supply, said pump also having a discharge cylinder for each engine cylinder communicating with said suction cylinder, a pipe connecting each discharge cylinder to an engine, and check-valves appropriately located to control the passages, substantially as set forth.
9. An apparatus for starting internal combustion engines comprising an explosive fuel supply, a pump formed with one suction cylinder connected with said fuel supply, another discharge cylinder connected with the engine cylinder, means for permitting the charge to flow from the suction cylinder to the discharge cylinder at the limit of the suction stroke, means for closing

ing the outlet from the discharge cylinder during the suction stroke, and means for closing the inlet to the suction cylinder during the discharge stroke, substantially as set forth.

In witness whereof, we have hereunto set our hands and seals at Indianapolis this

28th day of October, A. D. nineteen hundred and eleven.
